UNITED STATES PATENT OFFICE

PETER J. LUNATI, OF MEMPHIS, TENNESSEE

CHOCK

Original application filed June 9, 1925, Serial No. 36,019. Divided and this application filed February 24, 1926. Serial No. 90,399.

This invention relates to chocks and is a division of my copending application Serial No. 36,019, filed June 9, 1925.

An important object of the invention is to provide a novel form of chock particularly adapted for use in connection with vehicle supporting rails such as are shown in my copending application above identified and also shown in my copending application Serial No. 76,856 filed December 21st, 1925.

A further object is to provide a chock having means for supporting it on a vehicle rail, the chock being adapted to be swung outwardly from the rail to permit a vehicle to be driven upon and to leave the rails.

A further object is to provide a chock of the above mentioned character provided with means for limiting the swinging movement of the chock outwardly from the rail.

A further object is to provide a chock having means carried by a vehicle rail for supporting the chock thereon, the supporting means being adapted to slide longitudinally of the rail to permit the chock to be arranged in any desired position thereon.

Other objects and advantages of the invention will become apparent during the course of the following description.

In the drawings I have shown one embodiment of the invention. In this showing:

Figure 1 is a perspective view of a vehicle lift and turn table showing the invention applied.

Figure 2 is a fragmentary plan view of a vehicle rail showing the invention applied.

Figure 3 is a detail section on line 3—3 of Figure 2.

Figure 4 is a similar view showing the chock in inoperative position.

Figure 5 is a section on line 5—5 of Figure 2, and,

Figure 6 is a detail perspective of the chock.

Referring to the drawings, the numeral 10 designates a piston which is adapted to reciprocate vertically in a cylinder arranged beneath the surface of the ground. Means (not shown) is provided for introducing

fluid under pressure into the interior of the cylinder to elevate the piston. Supporting arms 11 are carried by the upper end of the piston, and the ends of the arms diverge outwardly substantially radially of the piston and are adapted to support vehicle rails. 55 12. The surface of the earth or other support upon which the apparatus is arranged, is provided with a circular depression 13 in which the arms 11 are arranged when the piston 10 is lowered. The elements described form no part of the present application but are described in my copending applications Serial Nos. 36,019 and 76,856 above identified. 60

Each of the rails 12 is substantially U-shaped in cross section, having a base 13 and upstanding flanges 14. In the use of the apparatus, as described in my copending applications, a vehicle may be driven upon the rails 12 while the latter are in lowered position, whereupon the piston 10 may be elevated to permit work to be performed beneath the vehicle, such as oiling the springs, etc. The piston 10 is rotatable 70 within the cylinder referred to whereby the upper structure may be rotated to serve as a turn table. When a vehicle is arranged on the rails, and it is desired to rotate the rails or elevate them, it is obviously desirable to provide some means for preventing movement of the vehicle longitudinally of the rails. Accordingly, I provide a chock 75

designated as a whole by the numeral 15 adapted to be arranged on either or both of the rails 12. The chock comprises a block of relatively heavy metal, preferably stamped steel, and includes an upper portion 16 intermediate its ends, arranged above and parallel to the base 13 of one of the rails. 80

At one side of the horizontal portion 16, the block is provided with a downwardly inclined end 17 which is adapted to engage one of the wheels of a vehicle in a manner to be described. The opposite end of the block is turned downwardly substantially at right angles to the intermediate portion 16, as shown at 18. The horizontal portion 16 is provided with preferably integral laterally extending fingers 19, and 85

each of the fingers is provided with loops 20 at its end for a purpose to be described. A stop lug 21 is formed integral with and stamped from the metal of the block preferably between the fingers 19, as clearly shown in Figure 6.

Referring to Figure 6, the numeral 21' designates a supporting member for the block preferably formed of stamped steel or the like. The supporting member is substantially inverted V-shaped having inner and outer arms 22 and 23 adapted to embrace one of the flanges 14 of the rail, as clearly shown in Figures 2 and 4. The support is provided with an integral lip 24 looped at its end to receive a pivot pin 25 which also passes through the loops 20 to provide a pivotal connection between the block and supporting member.

20 The operation of the device is as follows:

As previously stated the device is particularly adapted for use in connection with the vehicle lift and turn table described in my copending applications above identified.

25 When it is desired to lift a vehicle to permit work to be performed thereunder, the vehicle is driven on the rails 12 with the chock normally in the position shown in Figure 4, the rails being clear throughout their length. When the device is in proper position the blocks are swung inwardly to the

30 position shown in Figure 3, whereupon the supports 21' are adapted to slide to permit the blocks to be brought into contact with the vehicle wheels. It is only necessary to use the chocks on one of the rails but it will be obvious that they may be employed with both rails, if desired. The inclined portions 17 are arranged in contact with the

40 vehicle wheels, as will be apparent. The stop member 21 is adapted to engage the outer face of the support to limit the downward movement of the block when in inoperative position, as shown in Figure 4.

45 After the chocks are arranged in operative position it will be apparent that the piston 10 may be elevated and rotated freely, the vehicle being prevented from moving longitudinally along the rails by the chocks.

50 After the apparatus has been lowered and it is desired to drive the vehicle from the rails, the chocks may be slid inwardly a sufficient distance to permit the inclined portions 17 to clear the wheels, whereupon the

55 blocks may be swung outwardly to the position shown in Figure 4. When the block is in operative position the lower edges of the inclined portion 17 and the vertical portion 18 contact with the upper face of the base 60 of the rail to effectually support the block as will be apparent.

It is to be understood that the form of the invention herewith shown and described is to be taken as a preferred example of the same and that various changes in the shape,

size and arrangement of parts may be resorted to without departing from the spirit of the invention or the scope of the subjoined claims.

I claim:

1. A chock for use with a rail having a horizontal base portion and a vertical edge flange, said chock comprising a substantially inverted V-shaped supporting member adapted to slidably receive the edge flange of the rail, and an integral block pivotally connected at one edge to said supporting member, said block having one vertical wall adapted to contact at its lower edge with the base portion of the rail and an inclined wall adapted to contact with a wheel of a vehicle.

2. A chock for use with a rail having a horizontal base portion and a vertical edge flange, said chock comprising a substantially inverted V-shaped supporting member adapted to slidably receive the edge flange of the rail, an integral block arranged over the base portion of the rail, said block including a horizontal portion having one edge arranged adjacent said supporting member, one end of said block being turned downwardly substantially vertically and having its lower edge normally contacting with the base portion of the rail, the opposite end of said block being inclined and adapted to contact with a wheel of a vehicle, and a hinge connecting said supporting member with the horizontal portion of said block.

3. A device constructed in accordance with claim 2 provided with means for limiting the turning movement of said block about said hinge.

4. A chock for use with a rail having a base portion and a vertical edge flange, said chock comprising a substantially inverted V-shaped supporting member adapted to slidably receive the edge flange of the rail, a block adapted to be arranged on said base, and a hinge connecting said block and said supporting member to permit the former to swing upwardly and outwardly from the rail.

5. A chock for use with a vehicle supporting rail having a substantially horizontal base and an upstanding flange, said chock comprising a block for obstructing the rail to limit movement of a vehicle wheel thereon, a support slidably carried by the upstanding flange of the rail, and a pivotal connection between the block and support permitting the block to be moved laterally of the rail into obstructing position upon the base of the rail and out of obstructing position free from the base of the rail.

In testimony whereof I affix my signature.

PETER J. LUNATI.
